[57] CLAIM

The ornamental design for a shelf link, as shown and described.

DESCRIPTION

FIG. 1 is a bottom perspective view of a shelf link with the broken line showing of a fragmented support, shelving and a second shelf link being for illustrative purposes only and forming no part of the claimed design;

FIG. 2 is a top perspective view of a single shelf link;

FIG. 3 is a top view shown in FIG. 2;

FIG. 4 is a bottom view;

FIG. 5 is a front view, the rear view being identical; and,

FIG. 6 is an end view, the opposite end view being identical.
